ATTORNEY

UNITED STATES PATENT OFFICE.

KAUFMANN KAUFMANN, OF NEW YORK, N. Y.

MANUFACTURE OF PLATED WIRE.

SPECIFICATION forming part of Letters Patent No. 268,687, dated December 5, 1882.

Application filed August 23, 1882. (No model.)

To all whom it may concern:

Be it known that I, KAUFMANN KAUFMANN, of the city, county, and State of New York, have invented certain new and useful Improvements in the Manufacture of Seamless Roll-Plated Wire, of which the following is a specification.

In the manufacture of plated jewelry there has been used heretofore roll-plated wire, the filling of which is of base or composition metal, while the exterior layer or plating is gold or other fine metal. This plated wire was obtained by forming a plate of composition metal and a layer of gold into a tube, which was soldered at the seam, filled by a composition core, and then drawn or rolled, with the interior filling, to the thickness of wire required for use. As the seam is always more or less visible, care has to be taken, in the manufacture of plated jewelry from such wire, that the seam is always brought to the inside of the links, or other parts made therefrom. This requires considerable care in manufacturing articles of jewelry therefrom, and has furthermore the disadvantage that by wear the seam becomes oxidized, so as to show the interior filling.

My invention is designed to furnish an improved method of manufacturing drawn or roll-plated wire for jewelry, in which the seam is entirely done away with, and consequently a roll-plated wire furnished for use in the arts; and the invention consists, first, of an improved method of covering composition stock with a seamless plating, and, secondly, of a seamless drawn or roll-plated wire, as a new article of manufacture.

In the accompanying drawings, Figures 1 to 5 represent the method heretofore in use of making drawn or roll-plated wire for jewelry, and Figs. 6 to 10 show the different steps of making seamless drawn or roll-plated wire according to my improved method.

Similar letters of reference indicate corresponding parts.

In manufacturing seamless roll-plated wire according to my improved method, I first apply to a square plate, A, of composition stock of suitable thickness, by hard soldering, a thin layer or plate, B, of gold or other fine metal until an intimate connection of the two plates is obtained. From this compound plate a disk-

shaped blank is cut. This blank is next drawn into the shape of a hollow cylinder, closed at one end, by means of proper dies, in such a manner that the fine metal is at the outside. 55 This cylindrical blank is next filled with a core, C, of composition metal, and the whole then drawn or rolled out and reduced to the proper thickness of wire required, forming thus a seamless drawn or roll-plated wire, (shown in 60 Figs. 9 and 10,) that can be used with great advantages in the jeweler's or other arts, as all the different parts of the articles of jewelry can be formed therefrom at a considerable saving of time and labor, as the care required for the special location of the seam in the roll-plated jewelry heretofore manufactured is entirely dispensed with.

In place of forming the hollow cylindrical blank from a compound plate the gold plate 70 may first be formed into shape by suitable dies and then filled with composition metal, the filled blank being then drawn or rolled to the proper thickness and shape in the same manner as heretofore described.

The wire produced by the method described has a seamless plating of gold stock which encloses entirely the filling of composition stock adhering thereto intimately by the pressure asserted thereon in drawing or rolling, as contradistinguished from the plating obtained by electro-deposition.

By the use of such wire in the manufacture of jewelry—such as gold chains, ear-rings, bracelets, and other articles—a considerable 85 saving of time and labor is accomplished, as the wire can be worked up into any shape without special adjustment, while the quality and durability of the articles of jewelry manufactured therefrom are considerably enhanced 90 and a more substantial and finished appearance imparted to the same.

Having thus described my invention, I claim as new and desire to secure by Letters Patent—

1. The method herein described of making 95 seamless drawn or roll-plated wire, which consists of the following steps: first, forming a disk-shaped blank of composition stock and gold plate, or of gold alone, then drawing the same into the shape of a hollow cylinder closed 100 at one end, then filling said cylinder with inferior metal, and finally drawing or rolling the

so-formed cylindrical blank to the proper shape and thickness required, substantially as set forth.

2. As a new article of manufacture, seamless drawn or roll-plated wire for jewelry, formed of a filling of composition stock and an exterior seamless layer of fine stock, substantially as set forth.

In testimony that I claim the foregoing as my invention I have signed my name in presence of two subscribing witnesses.

KAUFMANN KAUFMANN.
